UNITED STATES PATENT OFFICE

JAMES POWERS, OF NEW YORK, N. Y., ASSIGNOR, BY MESNE ASSIGNMENTS, TO REMINGTON RAND INC., OF NEW YORK, N. Y., A CORPORATION OF DELAWARE

SELF STARTING AUTOMATIC TOTAL TAKING MECHANISM

Application filed October 16, 1924. Serial No. 743,940.

This invention relates to automatic tabulating machines having automatic total taking mechanism and controlled by analyzers or sensing mechanisms in turn controlled by perforations or designations in record cards, though it is noted that in some respects the present invention is not limited to tabulating machines nor even to perforated-card-controlled machines.

10 Heretofore, I have invented several machines of this type having mechanisms for automatically initiating and taking totals and resuming operation at the ends of the successive groups of record cards. The present 15 invention relates to improvements over these and similar machines.

In one type of machine I provided what are called spacing and total cards which are interposed between the respective groups to be 20 totalled, these cards properly controlling the sequence of necessary operations for effecting correct total taking, the space card causing the required idle revolution of the adding machine before taking a total, the total card 25 initiating the total taking operation. In large installations, the expense of making these special cards and loss of time in inserting them in the proper places is very great, and one object of the present invention is to 30 do away with the use of such cards, and hence with the expense and loss of time.

When inserting these cards, sometimes the operator fails to insert the cards in the proper place, or fails to insert one or both at the end 35 of some group, or fails to insert the separate spacing and total cards in the proper sequence. These failures cause errors and attendant confusion, delay and necessity of repetition of work, which of themselves are 40 costly and may sometimes result in irreparable injury.

In another type of machine invented by me, the total taking is initiated by the change in the location of the groups designating perforations between the respective groups. For 45 operating this type of machine, the perforations designating the class to which each group of cards belongs must have the same arrangement and location on the respective 50 cards, which arrangement and location must

be different from that of the cards of the preceding and succeeding groups. When the groups of cards pass through the designation change sensing portion of the analyzing mechanism, this mechanism senses the change at the end of each group and brings about the taking of the total.

In this type of machine the class-designating perforations of each class group must be the same throughout the group and must be different from the adjacent groups. In other words, it is not possible to depend upon this method of taking totals if the designating perforations of all the groups are the same, as the machine could not sense the change from one group to the next; or if the designating perforations of any group were not the same, as when the cards were mixed or contained cards of one or more classes, as then the totals would be taken at random throughout the group; or if the class designating perforations were omitted entirely, as when the classifying matter is written or printed. It is an object of the present invention to provide a machine which will automatically bring about the taking of a total, and subsequent resumption of adding on the next card group, independently of the presence or absence or arrangement or location of any designating or classification perforations as distinguished from amount perforations. For example, in many instances the perforated record cards are of paper of different colors to distinguish the different departments in which they belong or the different items of business to which they relate.

In such case, differently colored card groups could be placed in the magazine successively, for instance, brown, green, yellow, red, white or the like; and as each group of a certain color of paper is fed through the machine, a total of that group will be taken automatically and the adding operation of the machine on the next group resumed. The only perforations required on the cards are the amount perforations for adding. If the total number of cards of a series of groups are to be printed only a single counting perforation would be required for use with the machine shown herein, though the invention is not lim- 100

ited in its broadest aspect to a machine that requires perforations for counting or even to mathematical operations.

Another object is to provide an analyzer disabler, operating without the use of a spacing card or without stopping the analyzer pin box, for disabling the analyzer to permit the required idle or spacing cycle before total taking as explained above.

10 Another object is to provide in an account-
ing or other machine of this type, a card
feeling means in the feeding means itself,
whereby operations controlled thereby may
be initiated at an early instant, thus giving
15 the various mechanisms more time to act than
is the case where the feeler is in the analyzer.

Still other objects of the invention are to
improve generally the simplicity and effi-
ciency of card control mechanisms and to pro-
20 vide apparatus of this kind which is durable,
economical to manufacture, easy to operate
and which will not easily get out of order.

Still other objects of the invention will ap-
pear as the description proceeds; and while
25 herein details of the invention are described,
various changes may be made without depart-
ing from the scope of the invention as
claimed.

The inventive features for the accomplish-
30 ment of these and other objects are shown
herein in connection with a tabulating ma-
chine which includes an adding machine hav-
ing a card analyzer provided with yieldable
35 analyzer pins adapted for passing through
perforations of the cards. A magazine for
holding groups of the cards supplies them to
a picker mechanism for feeding the cards
from the magazine to the analyzer. The
magazine is constructed for permitting the
40 passage of one card group and then prevent-
ing the passage of the next group until the
magazine is shifted. A feeler feels the cards
being fed and as soon as all of one group is
fed, the feeler senses the absence of cards and
45 thereupon actuates a shifting mechanism for
shifting a retaining plate for holding down
the analyzer pins and thus disabling the
analyzer when no card is fed thereto to per-
mit the adding machine to complete the add-
50 ing and total taking operations which the
raising of the analyzing pins would inter-
fere with. A total initiating mechanism in-
cluding a rock shaft and a clutch is also con-
55 trolled by said feeler and actuates tripping
means which causes the machine to take the
total and clear the machine at the proper
time after the completion of the adding oper-
60 ation. Said initiating mechanism also brings
about the shifting of the magazine to permit
the feeding of the next group and the re-
sumption of the operation of the machine.

Fig. 20 is a fragmental side elevation showing the magazine shift mechanism in one of its home positions and part of the total initiating means in its home position.

My improved automatic total taking mechanism is shown in connection with an automatic accounting machine of the general type shown in my United States Patents Nos. 1,245,502 and 1,245,506 issued Nov. 6, 1917; and also the United States Patent No. 1,388,271 issued Aug. 23, 1921.

This accounting machine comprises an adding machine 10 mounted on a frame 11 carrying a card analyzer and feed means later to be described.

The analyzer comprises fixed upper and lower spaced perforated analyzer plates 12 and 13 (Fig. 12) between which perforated cards are fed. A vertically reciprocatory pin box 14 carries yieldably projected analyzer pins 15 adapted to pass through the perforations 16 (Fig. 14) in the lower plate to engage the card 17 at points where no perforation exists in the card or to pass through perforations in the card and into the registering perforations 18 of the upper plate, where they engage and raise terminal pins 19 slidably disposed in said perforations 18 and in similar perforations in a plate 20. Said terminal pins in turn engage and raise extension rods 21 resting on the terminal pins for controlling the registering of numbers and the like in the adding machine 10.

The feeding mechanism

Pairs of opposed feeding rolls 22, (Fig. 12) adjacent to the analyzer, feed cards into the analyzer from a feeding mechanism comprising a picker supporting frame 23 (Figs. 1, 2 and 5) adjacent to the said rolls and provided with guide channels 24 (Fig. 5) across the ends and a throat block 25 at the discharge side. An elongated picker block 26 on said frame is provided with a pair of end shoes 27 (Fig. 5) slidable in said guide channels 24. The picker block is continuously reciprocated by means of a picker lever 28 (Fig. 7) actuated from a cam 29 (Fig. 12) on the main shaft 30 as described in said patents.

A picker blade 31 secured on the rear of said block projects a short distance through a slot in a card supporting plate 32 mounted fast on the picker block and provided with a rear extension 33 and a pair of forward extensions 34 (Fig. 5) forming therebetween a forward opening 35 for the reception of the throat block 25 as the picker block moves for-

ward. A card positioning guide frame or container 38 (Fig. 3) mounted on said picker supporting frame is provided at its forward end with a horizontal slit 39 forming an elongated member 40 cooperating with the throat block 25 to form the card gate or throat 41 through which cards are projected by the picker blade to the feed rollers 22. The member 40 is adapted to be sprung toward the throat block by an adjusting screw 75 as shown.

The card magazine

A magazine base 43 resting on said guide frame or container 38 is provided at one end with a boss 44 pivotally received on a bearing bushing 45 carried in a projection 46 of the frame 23. A bolt bracket 47 at the opposite end of said base is provided with a vertical bore 48 having an enlarged lower portion 49. A bolt 50 slidable in said bore is provided at the upper end with a manipulating wheel 52 and at the lower end with a collar 53 guiding the bolt in the bore at the lower end. A spring 54 in said enlarged portion 49 compressed between the shoulder formed by said enlarged portion and said collar presses the bolt into an opening 55 to hold the card shaped opening 56 of said base in registration with the guide frame 38. A retaining member 57 mounted on said frame is provided with an undercut groove in which may be engaged an arcuate projection 58 on said collar 53 to hold the bolt in locked position. When the bolt 48 is unlocked and raised the base 43 may be swung entirely clear of the guide frame 38, thus to give unobstructed access to the picker. A gear plate 60 rotatably disposed in an annular groove 61 of the magazine base and on bearing ribs 62 of said base is provided with an intramarginal cross-shaped opening or card reservoir 63 (Figs. 2 and 3). The opposite ends of this opening are adapted to register with said card shaped opening 56 of the container 38 of the base when the gear plate is disposed at either of its two normal positions at right angles to each other. A retaining ring 64 fast on base 43 holds said gear plate in position and carries a stop pin 65 adapted to be engaged by stop plates 66 mounted fast on said gear plate 60 to stop said plate in the registering positions. Card end guides 68 mounted on said gear plate are formed with end and side walls 69 and 70 for engaging and positioning the cards 17 to hold them in the crossed or staggered relation in which they are stacked, as shown in Fig. 4, before they are placed in the magazine. One corner 71 of one of each pair of end guides is bevelled to engage the cut-off corners 72 of the cards to prevent the misplacing of the cards in the end guides, so the cards cannot be fed backwards or upside down.

The lower cards of the lowest group, or all of the lowest group, if the group be small, 130

drop through the opening 56 into the guide frame 38, whereupon the lowest card rests on the supporting plate 32 to be engaged by the picker blade and fed through the card gate 5 to the feed rollers and thence to the analyzer. The feeding action continues until all of the cards are fed from the lowest group, the cards of the group next above in the meantime resting on the base 43 and the ribs 62 thereof, which thus act as a preventing means to hold said group from the picker. When the last card is fed from the lowest group, certain automatic actions, later to be described, are set up which causes the taking of the total of said lowest group and the shifting of the gear plate 60 and everything carried thereon through 90° to bring said next to the lowest group, which has now become the lowest group, into registration with the card shaped opening 56 and the guide frame 38, whereupon the feeding of cards is resumed. The gear plate 60 is slightly grooved to receive the ribs 62 to prevent cards getting between the gear plate and base when the gear plate is shifted.

If the card groups are small and of less height than the guide frame 38, the next to the lowest group will always be supported by the base 43 and thus carry the load of all the cards above and relieve the pressure on the lowest group and the picker. This is an important advantage of the present invention. With my former machine it was not possible to feed the cards properly when a large number of cards was placed in the magazine as the weight of these cards exerted too great a pressure on the picker, whereas with the present invention a hundred or more of these small groups can be placed in the magazine at once, while only the weight of the lowest group bears on the picker. This advantage permits a single operator to load one machine while other machines are working and thus attend several more machines than was possible with my former machine.

The suction card positioner

In my earliest machine, some difficulty was experienced in making the cards lie flat on the picker and throat block for effecting positive and reliable feeding. To remedy this it has been customary to place a flat weight upon the cards, but even this fails to give perfect results every time, especially when only one or a few cards are in the magazine. I overcome this difficulty by suction means which will now be described.

A suction pump 75 (Fig. 1) mounted on the motor supporting frame 76 and driven by the belt 77 from the motor 78 of the machine tends to create a vacuum in a suction pipe 79 (Fig. 6) extending from said pump to a suction orifice 80 (Fig. 7) through the throat block. A U-shaped pipe 81 extending to orifices 82 near the picker blade and ex-

tending through the picker block and the supporting plate 32 is connected by a flexible tube to said suction pipe, whereby suction from the pump acts to hold the cards firmly upon the plate 32 and the throat block as the cards are fed, thereby insuring the positive feeding of the cards.

This suction means is much more effective than the above mentioned weight and is positive and reliable even with a single card in the magazine.

The card feeler or sensing mechanism

The above mentioned automatic actions are brought about by the action of a card feeler 85 (Figs. 2, 3, 5, 7, 10 and 11) supported in a strap bracket 86 mounted on the base 23 at the rear face of the picker block to provide a vertical guideway for the thin feeler shank 87 (Fig. 10) disposed in said guideway with its edges in the direction of the path of the cards and provided at the rear edge with a recess 88. The upper end of the shank is provided with a flat head 89 for engagement with the bottommost card. A flat spring 90 (Fig. 3) mounted on the lower face of the picker supporting frame 23 engages the lower end of said shank and is just strong enough to raise the feeler when no card is resting thereon and weak enough to be depressed by the feeler when a single card rests thereon.

A pair of levers 93 (Fig. 5) disposed longitudinally to the picker block are intermediately fulcrumed, as at 94, on the lower face of said forward extensions 34 for movement in a horizontal plane and have their inner ends 95 disposed directly behind the shank 87 (Figs. 10 and 11), whereby when the feeler is depressed and said picker block is moved forward, said inner ends 95 will engage said shank and oscillate said levers. On the other hand, if said feeler is raised by said flat spring when no card is resting on the feeler, said inner ends 95 will engage in said recess 88 (Fig. 11) and said levers will not be oscillated.

When said levers are oscillated they project forwardly a pair of push rods 97 (Figs. 5 and 10) having their rear ends pivoted to the outer end of said levers 93 and provided intermediately with longitudinal slots 98 receiving retaining pins 99 mounted on said forward extensions 34 for retaining and guiding the push rods forwardly.

A rock shaft 100 (Figs. 9, 12, 16 and 17) disposed transversely across the machine below the path of the cards and mounted in the side frames of the machine for rocking movement is rocked back and forth once during each cycle of operation for a reason which will presently be stated, by means of an oscillating lever 101 having its upper end fast on said rock shaft and its lower end forwardly turned to form an elbow portion 103

(Figs. 12 and 17), and bifurcated to provide a pair of lateral members 104 engaging on both sides of the main shaft 30 for guiding the lever. A roller 105 mounted on the side 5 face of said elbow part engages in a lateral cam groove 106 of a cam 108 mounted on said main shaft. The major portion of said groove is concentric with the main shaft, a small portion 109 of the groove being inwardly curved to give a quick movement of 10 the oscillating lever 101 during the period of each cycle when the analyzer pins 15 are in their lower positions.

15 The analyzer disabler

Sleeves 110 (Figs. 9, 13, 14 and 16) loosely mounted on the rock shaft 100, for independent movement relative thereto carry fast thereon lever arms 111 (Fig. 13) adapted to 20 be pushed forward or clockwise by said push rods 97 against the action of springs 112. Lifting arms 115 (Figs. 13 and 16) also fast on said sleeves are each provided with a laterally turned flange 116 adapted whenever 25 the arms 111 are not pushed forward or clockwise to engage and raise a downwardly projecting cam edge 117 (Fig. 16) at the rear end of a dog 118 pivoted at its forward end to the upper end of an upwardly and forwardly inclined arm 119 fast on the rock shaft. A spring 120 yieldably holds the dog 30 depressed.

The rods 97 are normally projected each time the picker feeds a card forwardly thus 35 forcing the arms 111 and 115 forwardly and permitting the dog to fall. When the picker moves back, the rods 97 and the arms 111 and 115 are retracted by the springs 112, raising the dogs 118. Thus the dogs are lowered 40 once for each adding cycle of the machine, and this lowering takes place so that they are in their lowered positions at the time that the cam groove portion 109 is at the position of Fig. 12.

5 An upper shaft 123 (Figs. 13, 14 and 18) mounted in said frame for oscillatory movement above said rock shaft and above the path of the cards carries downwardly projecting arms 124 provided with radial notches 125 each adapted to receive a tooth 126 on its associated dog when the latter is raised thereby to rock said shaft 123 as the dog is rocked to the right. A short lever 128 fast on shaft 123 is pivoted to the end 55 of a forwardly extending shift bar 129 for shifting a retaining plate 130 disposed between said analyzer plates 12 and 13 for supporting the pins 19 and provided at its forward edge with an upturned lip 131 (Figs. 8 and 12) provided with perforations received on horizontal pins 132 fast in the forward edge of the upper analyzer plate 12 to prevent the retaining plate from sagging. The upwardly inclined rear edge portion 134 of said 65 retaining plate helps guide the cards into the

analyzer and carries a lug 135 provided with an upturned internally threaded projection 136 (Fig. 13) guided in a slot 137 and held in a lug 138 (Fig. 9) of the bar 129 by means of a screw 140 (Fig. 13) passing through said shift bar and received in said projection for holding the retaining plate fast with said shift bar.

When said shift bar 129 and retaining plate 130 and the notched lever 124 are in the position shown in Figs. 13 and 14, the perforations of the retaining plate align with the perforations of the analyzer plates; but when the last card of a group has been analyzed and the feeler recess 88 (Fig. 11) rises to receive 80 the ends 95 of the levers 93, said arms 111 and 115 are not pushed forward as in Fig. 14, but remain under the dog 118 whereby said shift bar and retaining plate are pushed forward, as in Fig. 15, and the perforations 142 of the 85 retaining plate move out of register with said terminal pins 19 and analyzer pins 15 and prevent the rising of the analyzer pins and the raising thereby of the terminal pins and the extension rods 21, thus to permit the adding 90 machine to complete the carrying process of the adding cycle before taking the total. This permits the disabling of the analyzer without the necessity of stopping the pin box, the latter being continuously reciprocated by 95 means of the pin box cams 143 (Fig. 9) carried on the main shaft 30 and engaging rollers carried on extensions 144 of the pin box as well known in my former machine.

100 The clutch and total initiating mechanism

A bracket 145 (Figs. 9 and 18) mounted on the frame of the machine a distance below said rock shaft 100 carries a short shaft 146 carrying fast thereon a toothed lever 147 105 (Fig. 18) provided at its upper end with gear teeth 148 meshing with teeth 149 of a downwardly projecting toothed sector 150 fast on upper shaft 123. The intermediate part of said toothed lever 147 is provided with a large 110 transverse clearance opening 151 receiving rock shaft 100, but out of contact with the rock shaft permitting the upright arrangement of the toothed lever as shown. An arm 155 fast on shaft 146 carries a pendant link 115 156 having its lower end pivoted to a cam lever 157 having its rear end pivoted to a bracket 158 on the base 159 of the machine frame and yieldably raised by a compression spring 160. A total initiating shaft 163 disposed across the lower part of the machine in bearing brackets 158 and 164 (Fig. 9) carries a crank 165 provided with a horizontal bore 166 receiving a clutch bolt 167 provided with a head 168 normally engaged by said cam 120 lever 157, which is slightly forwardly inclined away from the crank, as shown in Fig. 19, for withdrawing the bolt from the crank and normally holding it withdrawn 125 against the action of spring 169 compressed 129

between a shoulder 170 of the crank and a collar 171 on the bolt. A sleeve 173 (Fig. 19) rotatably mounted on shaft 163 is rotated by means of reduction gears 174, 175 (see 5 also Fig. 20), interposed between said sleeve and main shaft whereby the sleeve is rotated at half the speed of the main shaft. A disk 176 (Fig. 19), fast on said sleeve is provided with diametrically opposite lugs 177 adapted 10 to be engaged by said bolt when said cam lever has released it, whereby said total shaft is rotated until said head 168 again comes into engagement with the cam lever and is withdrawn from said lug, thereby giving the 15 total shaft only one complete rotation each time the upper shaft 123 is rocked as previously explained. A bearing sleeve 180 (Fig. 9) mounted in the machine frame carries a tripping shaft 181 in turn carrying a lever 20 182 (Fig. 20), provided at its free end with a roller 183 adapted to be engaged by a tripping cam 184 mounted on said total initiating shaft 163 after 180° rotation of the shaft. Said tripping shaft also carries a forwardly 25 projecting arm 185 connected by an upwardly extending link 186 to a forwardly projecting tripping link 187 intermediately fulcrumed on the upper end of the active arm 188 of a bell crank lever 189 (Fig. 12) fulcrumed at 30 its elbow part upon a bracket 190 on the machine frame and provided at its lower end with an anti-friction roller 191 engaging in a groove 192 of a total cam 193 carried on said main shaft. A tripping lug 195 carried on the 35 forward end of tripping link 187 is adapted to actuate a total shaft actuating mechanism 196 when link 187 is tripped by the action of cam 184 and moved longitudinally by said bell crank lever thereby to set the adding 40 machine for taking a total.

This actuating mechanism is well known as the one used on my former machine and includes a short fixed shaft 197 carried on the main frame and carrying loosely thereon an 45 upwardly extending arm 198 carrying a lateral pin 199 engageable by said lug 195. The shaft 197 also loosely carries an active arm 200 fast with said arm 198 and connected by a link 201 to a lever 202 fast on the total 50 shaft 203 of the adding machine, whereby when the link 187 is tripped into the position shown by the dot-dash lines in Fig. 12, and the lug 195 engages the pin 199, said total shaft is rocked and the total taking mechanism of the adding machine is set in operation. In order to hold the total shaft rocked long enough for the total taking operation to be completed, the arm 205, also fast with said arms 198 and 200, is caught by a latch 206 fulcrumed on the bracket arm 207 fast on said fixed shaft. After the total operation is complete, the latch 206 is engaged by the releasing member 208 on the cam 193 thus moving back the latch against the action of the spring 60 65 209. In Fig. 12 the total shaft 203 is shown

operated and latched, a condition brought about by the control of the cam 184 under the roller 183 and the operation of the lever 189 by the cam groove 192 of the cam 193 as it moves into the position shown in Fig. 12 70 which is its home position in adding operations.

The magazine shift

When each total is taken, the magazine 75 must be shifted through a quarter of a rotation to permit the next card group to be fed as previously stated during the description of the magazine. Mechanism for this purpose will now be described.

A magazine shift cam 210 (Fig. 20) on a cam shaft 211 in said bracket 164 provided with a lateral cam groove 212 is connected to the initiating shaft 163 by reduction gears 213 and 214 whereby shift cam 210 is rotated 85 by shaft 163 one half of a rotation for each complete rotation of the shaft 163. A shift link or bar 215, provided with a longitudinal series of rack teeth 216, carries a slot 217 at one end received on said cam shaft 211 and a guide slot 218 at the other end received on a guide pin 219 fast on an extension 220 on said bracket 164. A roller 223 on said shift bar engages in said groove 212 for shifting said link from one limit to the other for each half rotation of the shift cam. A vertical counter shaft 224 mounted in said extension carries fast on its upper end a pinion 225 (Fig. 19) engaging said rack teeth 216 and on its lower end is provided with a gear 226 engaging a smaller gear 227 on the lower end of a spindle 228 having its lower end mounted in said extension and its upper end mounted in said bearing bushing 45 (Fig. 3) on said picker frame 23. A drive pinion 230 (Fig. 2) loosely mounted on the upper end of spindle 228 engages the teeth 231 of the gear plate 60. A collar 232 fast on the upper end of said spindle is provided with a radial lug 233 resting on said drive pinion and engaging between the free ends of pawl-like members 235 pivotally mounted on the upper face of said drive pinion and having said free ends connected by a spring 236 for yieldably pressing them on said lug and into engagement with pins 237 mounted on said pinion for limiting the inward movement of said members thereby to position said pinion relative to said spindle, said spring permitting yielding movement between said spindle and drive pinion thereby to prevent the breaking of any 110 of the gears should the magazine be accidentally held stationary.

It will thus be seen that each time the shaft 163 is rotated, the cam 210 moves 180° and the bar 215 moves from one limit to the other and rotates the pinion 225, the gears 226 and 227, and the spindle 228, the pinion 230 and the gear plate 60, the teeth and diameters of said pinions, gears and gear plates being such 115 120 125 130

that one complete movement of the bar 215 gives a quarter rotation to the gear plate 60 and the parts carried thereon.

The operation

The cards are separated and arranged in crossed or staggered relation as shown in Fig. 4. If the groups correspond to perforations on the cards, this grouping is done on the sorting machine. If the grouping is according to colors not corresponding to any perforations of the cards, the grouping is done by hand, the various colors having previously been placed together. If perforated cards are grouped without regard to the perforations thereon, or if picture or printed cards or imperforated cards of any kind are grouped as for counting, the grouping will take place as the various cards are selected depending upon the manner of selection under the given circumstances.

The cards having been grouped or stacked as shown in Fig. 4, a suitable number of groups are placed in the magazine, the beveled corners 71 of the magazine (Fig. 2) and the beveled corners 72 of the cards insuring that they are properly directed. The lowest group should preferably register with the card shaped opening 56. The height of the end guides 68 and the card guide 38 need not be limited to the heights illustrated; and if the card groups are small, a large number of them may be placed in the magazine at once as hereinbefore fully explained.

Preferably the machine is started after the cards are in the magazine, since if not the machine will go through the action of taking and clearing zero totals, that is, taking a total with no number registered in the machine. If the lowest group is not in the card guide frame 38, the machine will take a zero total and shift the magazine 90° and drop the lowest group into the guide frame 38.

With the magazine loaded and with cards in the guide frame 38 and the machine started, the suction at the orifices 80 and 82 positions the lowest card to the picker blade and on the throat block, depressing the feeler 85, so that when the picker moves forward to feed the card to the feed rolls 22, the recess 88 (Fig. 10) will be out of register with the ends 95 of the levers 93 causing said levers to project forward the push rods 97 (Fig. 14) and push forward the arms 111 and 115 to permit each dog 118 to drop down as shown in Fig. 14. The dog 118 is in its lowered position at the time the cam groove portion 109 and lever 101 are in the position shown in Fig. 12. When the arm 119 is rocked as the dog is out of engagement with the notched arm 124, the shaft 123 is not rocked, the retaining plate 130 is not shifted to the position of Fig. 15, the sectors 150 and 147 are not rocked, the cam lever 157 is not low-

ered, the bolt 167 is not released and the total is not taken nor is the magazine shifted.

From the feed rolls, the cards pass between the analyzer plates 12 and 13 and since, as explained, the retaining plate 130 is not shifted, the cards are analyzed in the ordinary way and pass on to the usual card receptacle (not shown).

The above analyzing or registering operation continues until all of the cards of a group have been fed from the magazine.

Total taking operation

When the cards of any group are exhausted, the cards of the group next above are still resting crosswise of the card shaped opening 56 (Fig. 3) and on the base 43 (Fig. 2) so that no more cards can reach the picker until the magazine is rotated a quarter turn, as previously explained. When it thus happens that the last card is fed from the picker and no card rests on the feeler, the feeler will rise (Fig. 11) under the action of the spring 90 (Fig. 3), the ends 95 (Fig. 5) of the levers 93 (Fig. 11) will be received in the recess 88, the push rods 97 (Fig. 13) will not be pushed forward as the picker moves forward, arms 111 and 115 will not move forward and the dogs 118 will not be dropped down from the position of Fig. 13 when the cam groove portion 109 reaches the position of Fig. 12 and has moved the dogs to the left into the position shown in Fig. 13.

When the cam groove portion 109 passes the position of Fig. 12, it rocks the lever 101 and arm 119 in a direction clockwise to the position shown in Fig. 15, whereby the dog 118 moves the notched arm 124 to the position of Fig. 15, rocking the upper shaft 123 and shifting the plate 130 until the perforations 142 move out of register with the analyzer pins 15 to prevent the rising of the pins while the adding machine and pin box finish the cycle thus permitting the completion of the adding operation before the commencement of the total taking operation.

When the upper shaft 123 is thus rocked in this counter-clockwise direction, the sector 150 (Fig. 18) and associated parts cause the depression of the cam lever 157 and the release of the bolt 167 (Figs. 9 and 19) into engagement with one of the constantly revolving lugs 177, whereby the total initiating shaft 163 is given one complete rotation, bringing the bolt head 168 again into camming engagement with the cam lever 157 (see Fig. 19) and causing the withdrawal of the bolt from the lug 177 to permit the shaft 163 to come to rest. As the sleeve 173 rotates with half the speed of the main shaft, it is necessary to have two lugs 177 in order that a lug be presented to the bolt 167 once during every cycle of the machine.

This single rotation of the initiating shaft will cause the tripping cam 184 to move in

a counter-clockwise direction toward the roller 183, but the cam will not reach the roller until after the bell crank 189 has been normally rocked while the lug 195 is in raised position. Thus during the first half of the rotation of the initiating shaft, the total shaft 203 will not be rocked, the total taking mechanism will not be set and the main shaft and the pin box, which make 5 two cycles during the rotation of the initiating shaft will complete an idle cycle while the analyzer pins are being held down as above explained. This will give time for the completion of the adding operation, and 10 before the bell crank 189 is rocked again, the cam 184 will have reached the roller 183 and caused the rocking of the tripping link 187 to the position of the dotted lines so that the rocking of the bell crank 189 by the 15 cam groove 192 will cause the then lowered lug 195 to engage the pin 199 and the rocking of the adding machine total shaft 203, to bring about total taking, and the holding of the same in rocked position, to give time 20 for the total taking operation, whereupon the engagement of the releasing member 208 with the latch 206 permits the total shaft to 25 resume its normal position.

This single rotation of the initiating shaft 30 163 also brings about a half rotation of the shift cam 210 (Fig. 20) and the shifting of the shift bar 215 from one limit to the other. This shifting of the shift bar and the consequent rotation of the spindle 228 causes the 35 rotation of magazine supporting gear plate 60 (Fig. 2) through 90°, thus bringing the card group which was resting on the base 43 into registration with the card shaped opening 56 to permit said group, which has 40 now become the lowest group, to rest upon the picker and depress the feeler to prevent further rocking of the upper shaft 123 (Fig. 14) until the analyzing and adding of the next group is complete, as previously described. 45

The above operations are repeated as long as cards are supplied to the magazine.

When groups of cards are to be counted, one column or digit of the card and the 50 adding machine is reserved for this purpose, the index point "1" of this column of the card being perforated. The card groups are fed through the machine and the unit "1" is added by the machine each time; at the end 55 of the group the total of these units is the number of cards in the group. In this way cards may be counted which contain thereon only printed or written matter except for the single perforated index point "1".

50 I claim as my invention:

1. In combination, an adding machine having a card analyzer; a magazine for groups of cards; feeding means for feeding cards from one group in the magazine to the card 55 analyzer; preventing means for preventing

the passage of the remaining groups to the feeding means; a feeler for the cards being fed; means controlled by said feeler for disabling the analyzer to give the adding machine time to take a total; total taking means controlled by said feeler; and means controlled by said feeler for disabling said preventing means each time a total is taken and causing the resumption of feeding. 70

2. In combination, an adding machine having a card analyzer; a magazine for holding groups of cards; a feeding means for feeding the cards from one group in the magazine to the card analyzer; preventing means associated with the magazine for preventing the passage of the remaining card groups; a feeler for feeling cards being fed; retaining means controlled by said feeler for disabling the analyzer when no card is fed to permit the adding machine to complete the adding 80 operation; an initiating mechanism controlled by said feeler; means controlled by the initiating mechanism to cause the machine to take a total after the completion of the adding operation; and means actuated by said 85 initiating mechanism for disabling said preventing means.

3. In combination, an adding machine controlled by cards; and means sensitive to the arrangement of the cards for causing said 90 machine to take a total and then to resume adding. 95

4. In combination, a card analyzer having analyzer pins adapted to pass through cards presented to the analyzer; and a retaining 100 plate for automatically preventing the passage of said pins and thereby disabling the analyzer when no card is presented thereto.

5. In combination, an adding machine having a card analyzer having analyzer pins adapted to pass through cards for controlling the machine; and a retaining plate for automatically disabling the analyzer pins when no card is presented thereto. 105

6. In combination, an adding machine having a card analyzer to which cards are presented for controlling the machine; said analyzer including a pair of spaced perforated plates, and analyzer pins yieldably projected through the perforations of said plates; 110 means including a perforated retaining plate for automatically retaining the analyzer pins in retracted position wherever no card is presented between said spaced plates thereby to permit the adding machine to complete the adding operation; and means for automatically causing the machine to take a total after the completion of the adding operation. 115

7. In combination, a card analyzer including a continuously reciprocatory pin box 120 with analyzer pins; and means including a mechanical feeler for disabling the pins while the box still reciprocates. 125

8. In combination, a card analyzer including a continuously reciprocatory pin box 130

having analyzer pins; and means including a mechanical feeler for automatically disabling the analyzer pins when no card is presented thereto while the box still reciprocates.

9. In combination, an adding machine having a card analyzer including a pair of spaced perforated plates, and a continuously reciprocatory pin box provided with analyzer pins 10 yieldably carried thereon and yieldably projected through the perforations of said plates; and a shiftable perforated retaining plate for retaining the analyzer pins in retracted position.

15. 10. In combination, an adding machine having a card analyzer to which cards are presented for controlling the machine; said analyzer including a pair of spaced perforated plates, and a continuously reciprocatory pin box provided with analyzer pins 20 yieldably carried thereon and yieldably projected through the perforations of said plates; a perforated retaining plate disposed between said spaced plates and having perforations registerable with the perforations of the spaced plates, the retaining plate being shiftable for retaining the analyzer pins in retracted position; and means for shifting said retaining plate.

25. 11. In combination, an adding machine having a card analyzer to which cards are presented for controlling the machine; said analyzer including a pair of spaced perforated plates, and a continuously reciprocatory pin box provided with analyzer pins 30 yieldably carried thereon and yieldably projected through the perforations of said plates; means including a perforated retaining plate for automatically retaining the analyzer pins in retracted position whenever no card is presented between said spaced plates thereby to permit the adding machine to complete the adding operation; and means for automatically causing the machine to 45 take a total after the completion of the adding operation.

12. In combination, an adding machine having a card analyzer including spaced plates between which cards may be fed and 50 yieldably projected analyzer pins adapted to pass through said plates; control pins engageable by said analyzer pins for controlling the registering of the machine; a magazine for groups of cards; a feeding means for feeding cards from the magazine to the analyzer; preventing means for preventing the passage of the groups to the feeding means; a feeler for the cards being fed; a 55 perforated retaining plate normally permitting said analyzer pins to pass; an operative connection between said plate and feeler for shifting said plate to prevent the raising of said pins; total taking means controlled 60 by said feeler; and means controlled by said 65

feeler for disabling said preventing means each time a total is taken.

13. In combination, an adding machine controlled by record cards fed thereto; a magazine for holding the cards; a feeding means including a reciprocatory picker for feeding the cards from the magazine to the adding machine; and means preventing the passage of cards to the feeding means when a total is taken. 70 75

14. In combination, an adding machine controlled by record cards fed thereto; a magazine for the cards; a feeding means for feeding the cards from the magazine to the adding machine; means for preventing the passage of cards to the feeding means; and means initiated by the absence of a card in the feeding means for taking a total. 80

15. In combination, an accounting machine controlled by cards; means for feeding cards thereto; means for automatically disabling the feeding means when a total is to be taken; means sensitive to the absence of a card in the feeding means for causing said machine to take a total; and means for causing the feeding means to resume feeding. 85 90

16. In combination, an adding machine having a card analyzer; a magazine for groups of cards; feeding means for feeding cards from the magazine to the machine; preventing means for preventing the passage of the groups to the feeding means; a feeler for the cards being fed; total taking means controlled by said feeler; and means controlled by said feeler for causing a resumption of feeding after a total is taken. 95 100

17. In combination, an adding machine controlled by record cards fed thereto; a feeding means for feeding the cards to the adding machine; and card sensitive feeling means causing the taking of a total and the resumption of adding, both while the feeding means continues in action. 105

18. In combination, an adding machine controlled by record cards fed thereto; a feeding means including a reciprocatory picker for feeding the cards to the adding machine; and means causing the taking of a total while the picker continues to reciprocate. 110

19. In combination, an adding machine controlled by record cards fed thereto; a continuously operating feeding means including a reciprocatory picker for feeding the cards to the adding machine; and means causing the machine to take a total and to resume adding while the picker continues to reciprocate. 115 120

20. In combination, an adding machine having a card analyzer; a main shaft for driving the machine; a magazine for groups of cards; a feeding means for feeding cards from the magazine to the machine; preventing means for preventing the passage of certain of the groups to the feeding means; a feeler for the cards being fed; a continuously 125 130

oscillating rock shaft; arms fast on the rock shaft; a dog pivoted on each arm; an upper shaft; a notched arm fast on said upper shaft; means controlled by said feeler, when the latter is projected, for raising said dog to lock with said notched arm; total taking means controlled by said upper shaft; and means controlled by said upper shaft for disabling said preventing means each time a total is taken.

21. In combination, an adding machine having a card analyzer; a main shaft for driving the machine; a magazine for groups of cards; a feeding means for feeding cards from the magazine to the machine; preventing means for preventing the passage of the groups to the feeding means; a feeler for the cards being fed; an upper shaft controlled by said feeler; a cam lever operatively connected to said upper shaft; a total initiating shaft carrying a crank; a clutch bolt movable on said crank and engaged by said cam lever when raised for withdrawing the bolt; a disk rotated at half the speed of the main shaft and provided with opposite lugs with which said bolt tends to engage when released; a tripping cam on said initiating shaft; total taking means controlled by said tripping cam; and means controlled by said initiating shaft for disabling said preventing means each time a total is taken.

22. In combination, an accounting machine controlled by cards; a feeding means for the machine including a reciprocatory picker; a magazine base provided with a card shaped opening over said picker; a plate mounted to oscillate on said base and provided with a cross-shaped opening, both portions of which are adapted to register with said card shaped opening; a vertically movable feeler mounted forward of the picker; total taking means controlled by said feeler; and means for oscillating said plate a quarter of a turn each time a total is taken.

23. In combination, an accounting machine controlled by elongated cards; a feeding means for the machine; a magazine base provided with a card-shaped opening over said feeding means; a cross-shaped magazine over said base, the members of which are adapted to register with said card-shaped opening; total taking means controlled by the absence of a card in the feeding means; and means for giving said magazine a partial turn each time a total is taken.

24. In combination, an adding machine having a card analyzer; a feeding means therefor including a reciprocatory picker; a magazine base provided with a card-shaped opening over said picker; a plate oscillatory on said base and provided with a cross-shaped opening, one portion of which is arranged to register with said card-shaped opening in one position of said plate, and the other portion of which is arranged to register with

said card-shaped opening in another position of said plate; a feeler forward of the picker; an initiating shaft controlled by said feeler; total taking means controlled by said shaft; a magazine shift cam rotated from said initiating shaft at half the speed of the latter and means actuated by said shift cam for moving said plate from one position to another each time said initiating shaft is rotated.

25. In combination, an accounting machine controlled by cards each having one cut-off corner; a feeding means for the machine; a magazine base provided with a card-shaped opening over said feeding means; an X-shaped magazine over said base provided with card end guides formed with end and side walls for positioning the cards, one corner of adjacent guides being bevelled to engage the cut-off corners of the cards; said magazine having crossed openings, one of said openings registering with said card-shaped opening in one position of said magazine, and the other of said openings registering with said card-shaped opening in another position of said magazine; total taking means controlled by the absence of a card in the feeding means; and means for shifting said magazine each time a total is taken.

26. In combination, an adding machine; a magazine; a feeding means under the magazine for feeding cards from the magazine to the machine including a reciprocatory picker; a vertically movable feeler mounted forward of the picker provided with a rear recess; levers on said picker received in said recess in one position of said feeler; and total taking means controlled by said levers.

27. The combination of an accounting machine, a card analyzer for said machine, a total taking mechanism, a magazine for a plurality of groups of cards, said cards being arranged in successive dissimilar group relation, means for causing the first group of cards to be fed successively to said card analyzer, means for preventing the remaining group or groups of cards from feeding during the feeding of said first group, and means automatically operated when the last card of the feeding group leaves said magazine for operating said total taking mechanism.

28. The combination of an accounting machine, a card analyzer for said machine, a total taking mechanism, a magazine for a plurality of groups of cards, said cards being arranged in successive dissimilar group relation, means for causing the first group of cards to feed successively to said card analyzer, means for preventing the remaining group or groups of cards from feeding during the feeding of said first group, means automatically operated when the last card of the feeding group leaves said magazine for operating said total taking mechanism, and means automatically functioning during

said total taking operation for causing the next group of cards to be brought to position to feed to said analyzer.

29. The combination of a card analyzer, a plurality of groups of cards arranged in successive group relation, a total taking mechanism, means for feeding said cards to said analyzer whereby all of said groups of cards are gradually fed toward said analyzer, means operable at a predetermined time to discontinue the feeding movement of all of said groups except the group then feeding to said analyzer, and means functioning when relieved of the weight of the last card of the feeding group to actuate said total taking mechanism.

30. The combination of a card analyzer, a plurality of groups of cards arranged in successive group relation, a total taking mechanism, means for feeding said cards to said analyzer whereby all of said groups of cards are gradually fed toward said analyzer, means operable at a predetermined time to discontinue the feeding movement of all of said groups except the group then feeding to said analyzer, and means automatically operated to take a total of the feeding group.

31. The combination of a card analyzer, a plurality of groups of cards arranged in successive group relation, a total taking mechanism, means for feeding said cards to said analyzer whereby all of said groups of cards are gradually fed toward said analyzer, means operable at a predetermined time to discontinue the feeding movement of all of said groups except the group then feeding to said analyzer, and means automatically operated by the feeding of the last card of the feeding group to take a total of the feeding group.

32. In combination an accounting machine controlled by perforated cards arranged in a predetermined position, a device for holding said cards stacked with one group in said predetermined position and another group in a different position, means for moving the groups from one position to the other, and means sensitive to a change from one position to the other for causing said machine to tabulate.

33. In combination, a perforated card-controlled machine arranged for different types of operations, a device for holding the control cards stacked with cards of one group arranged in one position and cards of another group arranged in another position, means for moving the groups from one position to the other, and means sensitive to a change in the position of said cards for causing said machine to change from one type of operation to another.

34. The combination of a card analyzer, a plurality of groups of cards arranged in successive group relation, with the end of one group abutting the first card of the next

group, a total taking mechanism, means for feeding said cards one at a time to said analyzer, means operable before the last card of the group being analyzed is fed to cause the abutting relation of said last card with the first card of the next group to change to a spaced relation, and means operated by the break in card feeding caused by said space relation between the aforesaid two groups to cause operation of said total taking mechanism.

35. The combination of a card analyzer, a plurality of groups of cards arranged in successive group relation, with the end of one group abutting the first card of the next group, a total taking mechanism, means for feeding said cards one at a time to said analyzer, means operable before the last card of the group being analyzed is fed to cause the abutting relation of said last card with the first card of the next group to change to a spaced relation, and means operated by the break in card feeding caused by said space relation between the aforesaid two groups to cause operation of said total taking mechanism and to bring the next group of cards to analyzing feed position.

36. In a machine of the class described, the combination of an analyzer, a card magazine, means for feeding the cards of groups of cards to the analyzer, and means for controlling the feeding mechanism to withhold the first card of a succeeding group in the magazine for a short period of time after the last card of the preceding group has been fed.

37. In a machine of the class described, the combination of an analyzer, a magazine comprising means for supporting cards in groups and means for supporting one group in position to be fed out of the magazine and another group in another position, and means for causing the machine to take a total after the last card of a group has been fed out of the analyzer and before the next group moves into position to be fed out of the magazine.

38. In a machine of the class described, the combination of a card magazine adapted to receive groups of cards in abutting relation, means for feeding cards out of the magazine, and means for separating the group of cards to be first fed, from the remaining groups to cause adjacent cards of adjacent groups to be fed out in spaced relation.

39. In a machine of the class described, the combination with an analyzer, adding and total taking mechanism, of means for separating abutting groups of cards and feeding the groups in spaced relation to the analyzer, and means operable according to the separation between said groups for causing the machine to take a total.

40. In a machine of the class described, the combination of an analyzer, adding and total taking mechanisms, means for feeding groups of cards in spaced relation to the an-

alyzer, and means operable according to the spacing between said groups for causing the machine to take a total.

41. In a machine of the class described, an analyzer, means for feeding cards to the analyzer for tabulation purposes, means for continuing tabulation regardless of whether or not a card is in the analyzer, and means operable in the absence of a card in the feeding means for causing the machine to take a total as the last card is fed from the analyzer.

42. In combination with a machine of the class described capable of adding amounts represented by perforations in a card and of taking the total accumulated, of means operable by the weight of a card to control the machine to add and operable in the absence of a card to control the machine to take a total.

43. In a machine of the class described capable of tabulating and total taking operations, the combination of means for feeding the individual cards of a group to an analyzer, of automatic means for presenting a group of cards to the feeding means after the cards of a preceding group have been fed, and means operable as the last card of a group has been fed for causing a total taking operation and operated by the presentation of the succeeding group to cause the machine to resume tabulating.

44. In a card controlled machine, a card magazine having provisions therein for keeping groups of cards in separated positions, means operating upon the cards from said magazine arranged to be actuated to produce a different operation as each group of cards is exhausted from its position.

45. In a tabulating machine, card controlling mechanism including a card magazine, means incorporated in said magazine for maintaining cards separated into groups, a register having total taking mechanism controlled from apparatus associated with the card controlling mechanism and means actuated according to the separation of the cards in the magazine for setting the total taking mechanism to take a total.

46. In a tabulating machine, card feeding and analyzing mechanism, a card magazine and a card guide frame associated therewith, said card feeding means adapted to feed cards from said card frame to said analyzing mechanism and means operated when the cards in said frame are exhausted for automatically introducing a new supply of cards thereto from said card magazine.

Signed at New York, county of New York,
State of New York, this 10th day of October,
1924.

JAMES POWERS.
